UNITED STATES PATENT OFFICE.

ASHTON G. STEVENSON, OF CHICAGO, ILLINOIS, ASSIGNOR TO CHICAGO LINO-TABLER COMPANY, OF CHICAGO, ILLINOIS, A CORPORATION OF ILLINOIS.

RULE-BROACH.

1,168,601.

Specification of Letters Patent.

Patented Jan. 18, 1916.

Application filed June 17, 1912. Serial No. 704,142.

To all whom it may concern:

Be it known that I, ASHTON G. STEVENSON, a citizen of the United States, and a resident of Chicago, Cook county, Illinois, have invented certain new and useful Improvements in Rule-Broaches, of which the following is a specification.

My invention relates to improvements in devices for facilitating the ruling of type forms and has particular reference to a novel punching or broaching device with which line-printing slugs and similar rule-holding members can be readily and accurately perforated for the reception of lino-tabler rules.

The object of my invention is to provide a device by which suitable openings for receiving lino-tabler printing rules can be accurately, quickly and easily made in the upper edges of slugs or other rule-holding members; to provide a device which shall facilitate the production of identical and other rule-holding members for receiving and holding lino-tabler rules; to provide a device by means of which a plurality of slugs or other rule-holding members can be substantially simultaneously punched or broached for receiving lino-tabler rules; to provide a device of this character which shall be reasonable in cost, which shall be capable of accurate and easy adjustment for producing rule-holding members having rule-receiving openings in definite predetermined positions; and to provide a device for preparing a plurality of rule-holding members for the reception of lino-tabler rules to accurately conform to a similar pre-formed member having rule-holding openings in certain definite position.

My invention resides in a punching or broaching device which is adapted to support or hold a plurality of line printing slugs or similar rule-holding members in definite relation to each other and provided with associated mechanism by means of which the upper edges of the slugs can be readily punched or broached for the reception of lino-tabler rules while thus held.

My invention further resides in a device of the character described in which the punching devices and slugs being operated upon can be relatively adjusted for the purpose of producing spaced rule-holding openings in the upper edges of the slugs.

My invention further consists in a device

for punching rule-holding members for receiving lino-tabler rules which is provided with a grooved die adapted to receive and substantially fit the upper edges of the members to be punched, a punch associated with the die and adapted to be forced through the upper edges of the slugs while they are held by the die, and means whereby the die with the punch can be easily and accurately adjusted, relatively to the rule-holding members which are being operated upon, for perforating their upper edges in certain predetermined positions for receiving lino-tabler rules.

A further feature of my invention resides in a novel construction of die and punch whereby the punch automatically clears itself of chips as it is forced, upon one stroke, successively through the several slugs.

A further feature of my invention relates to the facility with which a plurality of slugs or similar rule-holding members can be produced which will be accurate duplicates of each other and of a given preformed slug having a plurality of spaced rule-receiving openings in its upper edge.

A further feature of my invention relates to a device of the above character provided with a plurality of punches of different shapes adapted to make openings in the upper edges of rule-holding members to receive rules of different forms, and having a single operating handle, associated with interlocking stops, so arranged that but one of the punches can be operated at a time.

My invention also consists in the various novel features of construction and in the arrangements and associations of parts, herein-after described and particularly pointed out in the appended claims, and by the collective coöperation of which the above and other objects are attained.

My invention will be more readily understood by reference to the accompanying drawings forming part of this specification and in which:

Figure 1 is a top plan view of a broaching device showing one embodiment of my invention; Fig. 2 is an enlarged vertical section through one of the broaches on the line 2-2 of Fig. 1; Fig. 3 is a side elevation of the device, the clamping member being shown in raised position. Fig. 4 is an end elevation of the device the main parts being

in the same position as illustrated in Fig. 1; Fig. 5 is a transverse section of the clamping member on the line 5—5 of Fig. 2; Fig. 6 is an enlarged fragmentary detail section through the die member on the line 2—2 of Fig. 1; Fig. 7 is an enlarged side elevation of one of the line printing slugs having inserted rules in position; Figs. 8 and 9 are enlarged perspective views of two forms of punches adapted to produce holes for two forms of lino-tabler rules; and Fig. 10 is an enlarged bottom plan view of the die plate; Fig. 11 is a perspective view showing a ruled printing type form having novel rule holding members made in accordance with my invention; Fig. 12 is an enlarged cross-section of the type form on the line x—x of Fig. 11; Fig. 13 is a side elevation of a modified form of gage for use with the device.

This present invention relates particularly to a device for broaching or punching rule-holding members for the reception of printing rules of the character illustrated and described in United States Patent No. 974,718 issued to me November 1, 1910. These rules have since become known as lino-tabler rules and, as shown in said patent, they may be of many different cross sections, and I have selected two of the usual or ordinary forms for use herein to illustrate the general idea of the application of my present invention. Lino-tabler rules are particularly adapted to be secured to or upon a surface of a type form, which surface is somewhat below the printing face of the form. The rules are intended for providing vertical printing rules on a printing form in which the type slugs are arranged transversely to the rules. These rules may be secured in many different ways, one of which is by means of slugs or by rule-holding members interposed between the slugs and provided with rule-holding openings in their upper edges, and this present invention is directed particularly to a device for conveniently producing the openings in these rule-holding members for the insertion of the lino-tabler rules.

It has been found that a very reasonably priced cross rule can be produced from type metal which rule will have the form of an ordinary linotype slug provided on its printing surface with a longitudinal rib or edge. These linotype slugs are made of type metal and my present invention has for its main purpose the production of a convenient device for making rule-receiving openings through or in these and similar rule holding members.

In setting up a tabular form for the printing of a table consisting of columns of figures, it is quite common to use a number of the cross rules at different places in the table and when these rules are used in con-

junction with vertical rules it is obvious that the openings produced in the various cross rules for the reception of each of the vertical rules should be in line, and my device is particularly adapted for punching or broaching a number of the cross rules at a time, the rules being held in definite relation with each other and the punch being passed through the rules successively at one operation, whereby the openings or holes in the several rules for the reception of each of the vertical rules, which it is desired to use, will be accurately in line with each other.

As illustrated in the drawings, my device comprises a base plate 1, which is long enough to receive and support the slugs 2 to be operated upon. The base is provided with a longitudinal wall 3 arranged parallel with each edge and adjacent thereto, and against which the slugs are placed and held while they are being punched. The wall is far enough removed from the adjacent edge 4 of the base plate to provide a shelf 5 upon which a preformed rule-holding slug 6 or other gage is adapted to be held in position for the purpose of defining the positions of the rule slots to be produced in the slugs 2. In order to place the slugs accurately in proper relation, I provide a horizontal stop pin 7 near one end of the wall 3 which projects over the base plate far enough to receive the ends of the slugs 2 and against which the slugs can be placed to accurately aline them. The opposite end 8 of this pin projects over the shelf 5 and serves to accurately place the same rule-holding member 6 in alinement with the slugs 2. The wall 3 also serves to support and guide a movable clamping member 9, which clamping member carries the punching or broaching mechanism. The upper part of the wall 3 is provided with a longitudinal, L-shaped slot 10 in which is mounted a sliding joint or hinge member 11. This hinge member 11 is held in the slot by means of a thin plate 12 which is secured to the rear face of the wall 3, and which plate serves to complete the slot 10. The member 11 is L-shaped in cross section and conforms accurately to the slot 10 and is movable longitudinally therein to position the clamp relatively to the slugs. It is retained against vertical removal by the overhanging portion 13 of the wall 3. This joint member is provided with a longitudinal hinge pin 14 upon which is mounted the clamp 9, the clamp being provided with suitable hinge lugs 15 for this purpose. This clamp member 9 extends rearwardly beyond the base plate 1 and its rearward end 15' serves as a clamping handle by which the clamp 9 can be held against the plate. The clamp carries a depending leg or pin 16 which is adapted to contact with the rear portion of the base plate 1 and to support 139

the clamp 9, when it is in contact with the base, in substantially parallel relation to the base. The slugs 2, as shown in the drawings, are each provided with a V-shaped longitudinal rib 17 on its upper edge and the device is arranged to receive a number of these slugs against the rear face of the wall 3 and positioned against the stop pin 7. The clamp 9 is cut away on its lower face 5 adjacent to the wall 3 to receive a hardened steel die plate 18 which is inserted and held therein. This die is provided with grooves 18' which substantially fit the V-shaped ribs on the upper edges of the slugs and these grooves 18' are spaced apart a proper distance to receive the ribs when the slugs are positioned against each other, as shown in the drawings. Beyond the die plate in the clamping member 9 are arranged two 10 parallel punches or broaches 19 and 19'. Each of these punches is carried in a rack 20 which is slidingly mounted in a slot 21 in the lower face of the clamp member 9 and is adapted to be moved back and forth 15 when the rack is moved back and forth in its slot. Each of these racks is normally held at the rearward limit of its movement against a stop pin 21', by means of a tension spring 22 which is connected to the rear end 20 of the rack and to the rear end of the clamp. These racks are arranged parallel with each other and are operated by means of a pinion 23 which is rig'd with a shaft 24 carried in suitable bearing lugs 25 and 26 secured to 25 the clamping member 9. This shaft is rotated by means of a hand lever 24' which is secured to one end of the shaft. The shaft is movable endwise through the bearing lugs 25 and 26 so that the pinion can be arranged 30 to coöperate with either of the racks 20. In order to prevent both of the racks being inadvertently operated at the same time, the shaft 24 is provided with a radially projecting pin 27 adjacent to one end and so spaced 35 from the adjacent end of the pinion 23 that there is just sufficient room between them to receive the bearing lug 25, when the shaft is moved endwise to the dotted position shown in Fig. 3 and in which position it 40 meshes with the other rack. When it is desired to operate the other rack and the shaft 24 is moved longitudinally, the pin 27 passes through a slot 28 in the bearing lug 25 to a position inside of the lug at which time 45 the opposite end of the hub of the pinion 23 is in contact with the inner face of the opposite bearing lug 26. It is obvious that during the longitudinal movement of the shaft which changes the position of the pinion 50 from one rack to the other, the shaft 24 cannot be revolved as at this time the pin 27 is in the slot 28.

The two forms of rule which I have illustrated, are known as "light" and "heavy" 55 face and these two forms substantially agree with the light and heavy face type which are commonly used. It is very desirable in preparing a form for these rules to be able to provide the slugs with openings to receive either of the two forms of rules 60 without removing the slugs from the device. I therefore prefer to make one of the punches or broaches, as 19, of a form to make an opening to receive a rule having a light face, as shown at 29, and the broach 65 19' to make a hole to receive a heavy face rule as shown at 30. The lower faces of the racks 20 are flush with the lower face of the member 9 and are adapted to be held in position by means of a cover plate 31 secured to the lower face of the clamping member. The broaches, which are triangular in shape, are arranged with one face 70 against the cover plate 31 and the forward ends of the racks are grooved to receive 75 these broaches. The rearward ends of the broaches are bent upwardly and the racks are provided with holes 32 to receive them, consequently when the broaches are laid 80 into the grooves in the racks with their bent 85 ends inserted into the holes 32, and the cover plate 31 is secured in position the broaches are securely held in their proper positions.

The forward ends of the slots 21 in which the racks 20 are movable extend within a short distance of the die plate 18 and they are curved, as shown at 33, which is the shape that they are conveniently made by the milling cutter, and I form the forward ends of the racks 20 of a similar shape so 90 that when the racks are forced to the forward limit of their movement, they will substantially fit the slots 21. This form of rack serves to support the broaches to the greatest extent possible. The portion 95 of the lower face of the clamping member 9, which lies between the forward ends of the rack slots 21, and the die 18 is grooved, as shown at 36, to permit the longitudinal movement of the broaches. These grooves 100 105 110 115 120 125 130

36 are formed to substantially fit the broaches and to serve as guides for the broaches when they are operated to broach or punch the slugs. The longitudinal ribs 37 which lie between the grooves 18', in the lower face of the die plate, are cut away in line with the broaches to permit the broaches to be passed therethrough and obviously each of the ribs 37 serves as a die for its next adjacent slug to support the rib of the slug against the pressure of the punch as the punch passes through the rib. The racks and the pinion are formed to coöperate to limit the forward movement of the racks. As shown in Fig. 2, the teeth of the pinion 125 rest upon the surface of the rack when the rack is at the forward limit of its movement and the pinion is thereby locked against any further rotation. I also provide another means of stopping the forward move-

ment of the rack, which comprises a stop pin 25' mounted in and projecting from both the inside and outside faces of the bearing lug 25 and arranged to contact with the stop pin 27 when the shaft 24 is rotated.

In Figs. 8 and 9 I have shown two forms of punches, the light-face punch having what may be termed a "shovel" end which has a cutting edge 38 arranged substantially at right angles to the body of the punch and which is formed by an inclined face 39. It will now be evident that as the punch or broach is forced through the rib of the slug it will remove a chip from the rib and make an opening similar to that shown in Fig. 7 at 29; but in order that the punch may be forced through a number of the slugs in succession the chip must be removed from in front of the punch and for this purpose I provide an opening 40 extending upwardly through the die plate 18, and this opening is arranged substantially above the punch so that as the punch moves forward the slanting face 39 thereof will raise the chip through the adjacent clearance opening 40 and the punch will thereby automatically clear itself of each chip before it cuts the hole in the next slug. In Fig. 9 I have shown the form of cutting end which I prefer to use with the heavy face punch. In this form the forward cutting edge 41 instead of being at right angles to the punch, is arranged at more or less of an angle thereto and the beveled face 42 is tipped somewhat to one side. It will, therefore, be obvious that as this punch passes through the ribs of the slugs the chips which it removes from the ribs will be forced laterally to a certain extent and therefore in connection with such punches I prefer to form clearance openings 43 at one side of the line of travel of the punch and in such a relation to the punch that the punch will automatically and easily lift or force the chip through the clearance opening as the punch is advanced to the next slug.

In order to hold the clamping member 9 in its desired relation to the slugs, I provide an eccentric clamp 44 mounted upon the hinge pin 14 between the slugs 15 of the clamping member and provided with a projecting handle 45 by means of which the cam can be rotated upon the pin 14 and thereby clamp the hinge member 11 and the clamp member 9 to and upon the wall 3, as clearly illustrated in Fig. 2.

My device is particularly adapted for use in connection with type-printing slugs which can be made on the linotype machine and it is convenient to produce on the linotype machine a slug having rule-receiving openings in the proper position in relation to the tabular matter which is being set up, and my device is adapted to make use of one 65 of these latter slugs having rule receiving

openings prepared, as indicated, as a guide for determining the places at which the rule-holding openings shall be made in the slugs 2 by the broaches. The sample slug, 6, as already stated, is placed upon the base at the rear face of the wall 3 and against the stop 8, and this sample slug is provided with a number of rule receiving slots, openings or notches 46 spaced as desired. In order to accurately set the clamping member 9 so that the slugs 2 will be broached for the rules in proper alinement with the rule openings 46 in the slug 6, I provide the device with two indicators 47 and 48 which are mounted upon the pin 14 at the opposite ends of the clamping cam 44. Each of these indicators is provided with a projecting tongue 49 which is adapted to be entered into the slots 46. The tongue 49 of each of these indicators is off-set to bring its free end accurately in line with one of the broaches or punches, and when the tongue of one of these indicators is placed in one of the rule-receiving slots in the sample slug 6 the clamp is thereby adjusted so that when the complementary punch is operated it will produce rule-receiving openings in the slugs 2 in accurate alinement with the rule-receiving opening or slot of the slug 6 in which the indicator arm rests. After the clamp has been thus adjusted, to accurate position, the eccentric 44 is operated to secure the clamp in this position. Should it now be desired to broach a greater number of the slugs than can be broached at one setting, the clamp 9 can be raised after the slugs have been broached, the slugs removed and another lot put in place to be operated upon, and consequently all the slugs of the series will be accurate duplicates of each other. To retain the sample slug or gage in position, I provide two retaining springs 50. These springs are secured at their lower ends to the rear edge of the base plate 1 and extend upwardly and inwardly to bear upon the slug 6. Their extreme upper ends are bent outwardly so that the slug 6 can be readily pushed into place beneath the springs, the springs bearing upon the rear face of the slug 6 and holding it in position against the rear face of the wall 3.

My device is equally applicable to the production of other than the line printing rule-holding members illustrated in Figs. 6 and 7, and in Figs. 11 and 12 I have shown some additional forms. Rule-holding members such as slugs 2 and shown in Figs. 6 and 7 are usually type high and are adapted to print cross lines when used in a form. Another novel form of rule-holding member is that shown at 51 in Figs. 11 and 12. This slug is cast with a continuous rib 51' on its upper edge quite similar to the printing rib 17 on the slug 2 except that it is lower than the rib 17 so that it will not print when

the form is used. This longitudinal rib 51' is perforated as at 52 in the same manner as the printing rib 17 and with the same facility and accuracy upon and by means of the 5 punching device.

Still another form of rule-holding member which can be punched upon the broaching device is that shown at 53 Figs. 11 and 12. This slug is what may be termed a printing 10 slug in that it may carry printing type 54 but it is also provided with the rule receiving openings produced in high quad-like projections 55 which are preferably lower than type high. These projections are adapted 15 to be produced upon linotype machines by the use of suitable matrices positioned in the line to form the projections in the proper relative positions on the slug and are afterward broached or punched by use of the 20 broaching device to receive the lino-tabler rules.

The sample slug 6 which is used upon the device for positioning the broach to produce the rule receiving openings in certain defined 25 positions in the slugs 2 can obviously be replaced by a prepared metallic gage 56 such as that shown in Fig. 13. This gage is quite similar to a linotype slug in that it is substantially of the same height but it is provided with a plurality of evenly spaced 30 notches 57 in its upper edge adapted to receive the gage fingers 49 to position the clamp as desired. These notches are preferably arranged in the gage slug a half pica 35 apart so that by means of this gage rules could be placed at substantially any point in the upper edges of the slugs.

While I have illustrated and described my device as being adapted for use in a horizontal 40 position, I do not wish to be limited to its use in such position, and as many modifications of my invention will readily suggest themselves to one skilled in the art I do not limit or confine my invention to the 45 specific structures herein shown and described.

I claim:

1. A broaching device for perforating the upper edge of a rule-holding member for receiving lino-tabler rules comprising a clamping member having a groove for receiving the upper edge of the member to be broached, a broach carried by said clamping member, and means for adjusting said clamping member relatively to the member to be broached. 55

2. A multiple punch for perforating printing-rule holding-members comprising means for holding a plurality of members in position to be perforated in combination 60 with a broach for making rule receiving openings in the upper edges of the members so held, means for guiding the punch relatively to the members, and means for adjusting the guiding means relatively to the members to be perforated for the purpose of

making rule receiving openings at different points in said members.

3. A punch for perforating the upper edge of a substantially type-high rule-holding member to receive a plurality of lino-tabler rules, comprising a clamping member adapted to receive the edge of the member to be perforated, a punch mounted in said clamping member to reciprocate substantially at right angles to said members, and means for adjusting said clamping member relatively to said rule holding member for spacing the rule receiving openings along the upper edge of the rule holding member. 70 75

4. In a punching device for simultaneously preparing a plurality of printers' slugs for receiving line printing rules, a clamping device for holding the slugs to be punched, a die carried by the clamping device and having a plurality of parallel grooves in its lower face substantially fitting the upper edges of the slugs, a V-shaped punch carried by the clamping device and adapted to be projected through a suitable groove in the lower face of the die, and means for moving the punch back and forth at right angles to the plane of the slugs. 80 85

5. In a punching device for simultaneously preparing a plurality of printers' slugs for receiving line printing rules, a clamping device for holding the slugs to be punched, a die carried by the clamping device and having a plurality of parallel grooves in its lower face substantially fitting the upper edges of the slugs, a V-shaped punch carried by the clamping device and adapted to be projected through a suitable groove in the lower face of the die, and means for moving the punch back and forth at right angles to the plane of the slugs, the die being provided with clearance openings through which the punch is adapted to force the chips cut from the slugs. 90 95 100 105

6. In a device for forming transverse openings in the edges of slugs for receiving lino-tabler rules a clamping device for holding the slugs, said clamping device having a plurality of parallel grooves adapted to receive the upper edges of the slugs which are to be operated upon, a punch carried by and movable in said clamping device at right angles to said slugs adapted to remove a chip from each of the slugs in succession as it is forced therethrough, said clamping member having clearance openings adapted to receive said chips as they are ejected from the slugs by the punch. 110 115 120

7. In a device for forming transverse openings in the edges of slugs for receiving lino-tabler rules a clamping device for holding the slugs, said clamping device having a plurality of parallel grooves adapted to receive the upper edges of the slugs which are to be operated upon, a punch having a transversely beveled cutting edge and carried by 125 130

- and movable in said clamping device at right angles to said slugs adapted to remove a chip from each of the slugs in succession as it is forced therethrough, said 5 clamping member having clearance openings passing therethrough and arranged in substantial alinement with the path of the punch adapted to receive said chips as they are ejected from the slugs by the punch.
10. 8. A punch for making lino-tablet rule receiving openings in the upper edges of line printing slugs and similar members comprising a base, a vertical wall thereon adjacent to one edge, adapted to position the 15 slugs for operation, a stop adjacent one end of the wall to retain the slugs in proper position, a sample slug resting on the base and held against the guide wall opposite to said slugs, said sample slug having a plurality of 20 spaced rule-receiving notches in its upper edge, the upper edge of said wall having a longitudinal guide groove, a hinge member fitting in said groove and adapted to slide back and forth therein, a clamping member 25 carried by said hinge member, grooves in the lower face of said clamping member fitting the upper edges of the slugs, a punch carried by said clamping member arranged at right angles to said grooves and adapted 30 to be projected through the upper edges of the slugs when the clamping member is in position thereon, an index finger carried by said clamping member having a projection in line with the punch and adapted to rest 35 in a rule-receiving opening in the sample slug to position the punch, means for clamping the hinge member to the guide wall to retain it in its adjusted position, means for moving the punch forward to form rule-receiving 40 openings in the upper edge of the slugs, and means for withdrawing the punch to its retracted position.
9. A device for punching rule-receiving openings through V-shaped printing edges 45 on line-printing type-metal slugs, each slug having a V-shaped rib on its upper edge narrower at its base than the thickness of the slug whereby the slug is provided with a substantially flat surface from which the 50 V-shaped rib rises, a clamping member having parallel V-shaped grooves spaced apart to receive the ribs of the slugs when the
- slugs are arranged compactly against each other, the clamping member being formed to substantially fit the V-shaped ribs and to 55 bear upon the flat upper faces of the slugs and thereby retain the slugs in position, a punch carried by the clamping member adapted to be forced through the ribs and to form inverted V-shaped openings therein, 60 the base of each of the openings being substantially flush with the flat top surface of the slugs, and means for adjusting the clamping member relatively to the slugs to produce rule-receiving openings therein at 65 certain predetermined points.
10. In a device for making rule-receiving openings in the upper edges of slugs or other rule-holding members, the combination with a clamping member having parallel grooves adapted to receive and substantially fitting the upper edges of the members 70 to be punched, two parallel punches carried by said clamping member adapted to form rule-receiving holes of different 75 shapes, adjustable means for operating either one of said punches, and means for preventing the operation of both of said punches at the same time.
11. In a device for making rule-receiving 80 openings in the upper edges of slugs or other rule-holding members, the combination with a clamping member having parallel grooves adapted to receive and substantially fitting the upper edges of the members 85 to be punched, parallel racks mounted in parallel grooves in the lower face of said clamping member adapted to be moved back and forth at right angles to said slugs, a punch carried by each of said racks and 90 adapted to form rule-receiving slots of different forms in the slugs, a single pinion for operating said racks adjustable from one to the other, and means for preventing the operation of said pinion except when in 95 full mesh with either of the racks.
- In testimony whereof, I have hereunto set my hand, this 15th day of June, 1912, in the presence of two subscribing witnesses.

ASHTON G. STEVENSON.
